DOOR STRUCTURE FOR A RENDERING COOKER OR THE LIKE

Lester S. Downey, Oak Lawn, and Ralph W. Illsley, Chicago, Ill., assignors to The Albright-Nell Company, Chicago, Ill.

Application May 12, 1954, Serial No. 429,204

4 Claims. (Cl. 189—46)

The present invention relates generally to door structures. More particularly, the invention relates to that type of door structure which is located at one end wall of the tank of a pressure variety rendering cooker and as its principal components or parts comprises: (1) a rectangular frame which fits and is fixedly secured within a correspondingly shaped opening in the lower portion of the one end wall of the tank; (2) a door which is hinged at its upper marginal portion to the upper portion of the frame in order that it is capable of swinging downwards into a closed position wherein it extends across and seals the frame and upwards into an open position; (3) a horizontal lock bar which embodies a fork at one end thereof and has its other end hinged to one side portion of the frame in order that it is capable of swinging horizontally into and out of an operative position wherein it extends across the outer surface of the door and serves to hold the door in its closed position; and (4) a nut-equipped eye bolt which is hinged to the other side portion of the frame, is adapted when the lock bar is in its operative position to have the shank thereof swung into seated relation with the fork, and is further adapted when its shank is in place and the nut thereon is tightened to clamp the lock bar against the door.

In a door structure of the aforementioned type, it is customary to form the door and the lock bar of cast iron. It is also customary to provide the central portions of the lock bar and the door with coacting male and female members which when the lock bar is in its operative position transmit clamping pressure from the lock bar to the door. In practice, it has been found that if the coacting male and female members for transmitting clamping pressure from the lock bar to the door are permanently secured in place, the male member in many instances does not properly interfit with the female member and hence the door when in its closed position is not properly retained or held in place by the lock bar.

One object of this invention is to provide a door structure which is an improvement upon, and eliminates the disadvantage of, previously designed door structures of the same general type and is characterized by the fact that one of the coacting members for transmitting clamping pressure from the lock bar to the door is loosely mounted in place so that it is movable laterally in all directions to a limited extent to the end that, in connection with swinging of the lock bar into its operative position, it will automatically adjust itself into correct or proper interfitting or seated relation with the other member.

Another object of the invention is to provide a door structure of the last mentioned character in which the female member is in the form of an integral socket-equipped pad on the central portion of the door, and the male member is in the form of a hemispherical head which fits flatly against the central portion of the lock bar and is loosely mounted in place by way of a horizontal bolt which extends through an oversized hole arrangement in the lock bar.

2

A further object of the invention is to provide a door structure of the type and character under consideration in which the lock bar is in the form of a hollow casting and the hole arrangement in the lock bar has associated with it a horizontal sleeve which prevents dust and other matter from entering the interior of the lock bar and surrounds loosely the bolt by which the male member is loosely mounted.

A still further object of the invention is to provide a door structure which is generally of new and improved construction and effectively and efficiently fulfills its intended purpose.

Other objects of the invention and the various advantages and characteristics of the present door structure will be apparent from a consideration of the following detailed description.

The invention consists in the several novel features which are hereinafter set forth and are more particularly defined by the claims at the conclusion hereof.

In the drawings which accompany and form a part of this specification or disclosure and in which like numerals of reference denote corresponding parts throughout the several views:

Figure 1 is a perspective of a pressure variety rendering cooker having applied thereto a door structure embodying the invention, the door of the structure being shown in its closed position and the lock bar of the structure being shown in its operative position;

Figure 2 is a fragmentary perspective like Figure 1 except that it illustrates the door of the structure in its open position and the lock bar in its inoperative position;

Figure 3 is a vertical section of the door structure showing in detail the construction and arrangement of the coacting male and female members for transmitting clamping pressure from the lock bar to the door;

Figure 4 is a horizontal section on the line 4—4 of Figure 3; and

Figure 5 is a perspective of the bolt-equipped hemispherical head that constitutes the male member of the coacting members for transmitting clamping pressure from the lock bar to the door when the door is in its closed position and the lock bar is in its operative position.

The door structure that is shown in the drawings constitutes the preferred form or embodiment of the invention. It is designed primarily to form a part of a pressure variety rendering cooker although, manifestly, it has other capabilities of use. The cooker is of conventional or standard construction and embodies a horizontally elongated cylindrical steam-jacketed tank 6. The latter as well understood in the art has disposed therein a coaxial shaft (not shown) which has radially extending paddles and is driven by an electric motor and suitable speed reducing gearing. In the lower central portion of one of its end walls, the tank 6 is provided with a substantially rectangular discharge opening 7. Such opening is so designed that its horizontal dimension is greater than its vertical dimension. As its principal components or parts, the door structure comprises a rectangular frame 8, a door 9, a lock bar 10, an eye bolt 11, a nut 12, a female member 13 and a male member 14. Except for the female member 13 and the male member 14, the door structure is of standard design. The female and male members coact as described hereinafter more in detail to transmit clamping pressure from the lock bar 10 to the door 9 in order to hold the latter in its closed position.

The rectangular frame 8 of the door structure is shaped conformably to, and is mounted in, the discharge opening 7 in the tank 6 of the rendering cooker. It is in the form of a one-piece metallic casting or forging and has its outer edge portions welded to the portions of the cooker tank that define the opening 7. A continuous outwardly extending flange 15 is formed as an integral

part of the frame 8, and this flange embodies at the upper ends of its side portions a pair of lug-like enlargements 16. The latter have coaxial holes 17 therein and serve as journals for a horizontal extending rock shaft 18. As shown in Figures 1 and 2, an arm 19 is connected to one end of, and extends radially with respect to, the rock shaft and forms a handle whereby the shaft 18 may be rocked back and forth.

The door 9 of the structure is formed of cast metal and is shaped and adapted to extend across and close the frame 8. It is provided at its upper corners with two integral apertured lugs 20 which are disposed inwards of the enlargements 16 and extend around the rock shaft 18. As shown in Figure 3 of the drawings, the lugs 20 are connected to the rock shaft 18 by way of keys 21 in order that the door 9 is in fixed relation with the rock shaft. The lugs 20 and the rock shaft form a hinge whereby the door is supported so that it is capable of swinging downwards into a closed position wherein it extends across and closes the frame 8 (see Figure 1) and upwards into an open position (see Figure 2). Swinging of the door into and out of its closed position is effected by manually manipulating the radially extending arm 19 on the rock shaft. The marginal portion of the door is provided with a continuous inwardly facing groove 22 in which a gasket 23 is mounted. When the door is in its closed position, the gasket 23 bears against the inner marginal portion of the frame 8 and forms a seal between the door and the frame.

The lock bar 10 of the door structure extends horizontally and is in the form of a hollow one-piece casting. It embodies at one end thereof an integral vertically extending sleeve part 24 and at its other end an integral outwardly extending fork 25 and is adapted when the door is in its closed position to extend across the door as shown in Figure 1. A vertically extending pivot pin 26 extends through the sleeve part 24 and forms with the latter a hinge whereby the lock bar may be swung back and forth between operative and inoperative positions. The ends of the pivot pin 26 extend through a pair of vertically spaced apertured lugs 27 and have transversely extending cotter pins 28 which coact with the lugs to hold the pivot pin 26 against axial displacement. The lugs 27 are formed integrally with, and project outwards from, one of the lower corner portions of the frame 8. The lock bar is of such length that when it is swung into its operative position wherein it extends across the door as shown in Figure 1, the fork 25 on the distal end of the lock bar extends beyond the adjacent side portion of the door.

The eye bolt 11 of the door structure is located adjacent the side portion of the frame that is opposite the side portion having the lugs 27. It is of one-piece construction and comprises a vertically elongated eye 29 and a horizontal shank 30 (see Figure 4). The eye 29 extends around, and is rotatably mounted on, a vertically extending pivot pin 31 in order that the shank 30, when the lock bar 10 is in its operative position, may be swung into and out of seated relation with the furcations of the fork 25 on the distal end of the lock bar. The ends of the pivot pin 31 extend through a pair of vertically spaced apertured lugs 32 and have suitable means for preventing axial displacement of the pivot pin. The lugs 32 are formed integrally with, and project outwards from, the adjacent lower corner portion of the frame 8.

The nut 12 of the door structure is rotatably mounted on the shank 30 of the eye bolt 11 and is provided with a hand wheel 33 whereby it may be turned in one direction or the other. It is contemplated that when the shank of the eye bolt is in seated relation with the furcations of the fork 25, the nut will bear against the outer portion of the fork as shown in Figure 4. When the nut is tightened by turning the hand wheel 33 in the proper

direction, the nut 12 feeds inwards and urges the lock bar towards the door 9.

The female member 13 and the male member 14 of the door structure coact to transmit clamping pressure from the lock bar to the door. The female member is in the form of a pad 34 which is formed integrally with the central portion of the outer surface of the cast metal door 9. Such pad is provided with a flat outer surface 35 in which is formed a substantially hemispherical socket 36. The socket is so positioned that it faces the central portion of the lock bar when the door is in its closed position and the lock bar is in its operative position. The male member 14 of the door structure is in the form of a hemispherical steel head 37, the radius of which corresponds to the radius of the socket 36 in the pad 34 constituting the female member 13. The head 37 has a flat surface 38 which fits flatly against an integral boss 39 on the central portion of the lock bar 10. As shown in Figure 3 the lock bar, because it is hollow, embodies inner and outer side walls and top and bottom walls between the side walls. The boss 39 is formed on the central portion of the inner side wall of the lock bar. In addition to the hemispherical head 37 the male member 14 comprises a horizontally extending stud-type bolt 40. The latter extends through oversized circular holes 41 and 42 in the inner and outer side walls of the lock bar 10 and serves with the holes as a loose mounting for the head. Such mounting permits the hemispherical head 37 to move laterally in all directions to a limited extent and hence when the lock bar is swung into its operative position, the head will automatically move into proper or correct interfitting or seated relation with the hemispherical socket 36. In connection with tightening of the hand wheel equipped nut 12 on the eye bolt in connection with a door clamping operation, the door swings upwards and the lock bar swings sideways. Under the circumstances, the female member 13 does not remain in a fixed position with respect to the central portion of the lock bar. By having the male member 14 loosely mounted, the head 37 constituting the male member will automatically adjust itself laterally so as to maintain proper seated relation with the hemispherical socket 36 in the pad 34. The end of the bolt 40 that extends through the hole 41 in the inner side wall of the lock bar is threaded and fits snugly within a screw threaded socket 43 in the central portion of the head 37. The other end of the bolt 40, that is, the end that extends through the hole 42 in the outer side wall of the lock bar, is provided with a washer 44 and a pair of lock nuts 45. The washer 44 as shown in Figures 3 and 4 fits loosely and slidably against a boss 46 on the central portion of the outer side wall of the lock bar. The lock nuts 45 are so arranged that they do not clamp the washer 44 against the boss 46 and hence the bolt 40 is always loosely mounted with respect to the oversized circular holes 41 and 42 in the inner and outer side walls of the lock bar 10. When the lock bar 10 is in its operative position, the female and male members 13 and 14 of the door structure operate as hereinbefore indicated to transmit the clamping pressure of the lock bar to the central portion of the door 9. In order to prevent dust or other foreign matter from entering the interior of the lock bar 10, a horizontal sleeve 47 is provided. This sleeve surrounds loosely the bolt 40, extends through the central portion of the lock bar, and has its ends connected by a press fit to the portions of the lock bar inner and outer side walls that define the holes 41 and 42.

The herein described door structure is both simple in design and efficient in operation and this is because it includes the coacting female and male members 13 and 14 for transmitting the clamping pressure of the lock bar to the door. Because the hemispherical head 37 of the male member 14 is mounted in place by way of the bolt 40 which is loosely positioned in the oversized holes 41 and 42 and the sleeve 47, it automatically adjusts itself

into proper seated relation with the socket 36 when the lock bar is swung into its operative position.

The invention is not to be understood to be restricted to the details set forth since these may be modified within the scope of the appended claims without departing from the spirit and scope of the invention.

Having thus described the invention what we claim as new and desire to secure by Letters Patent is:

1. In a door structure of the type that comprises a substantially vertical rectangular frame, a door part hinged at the upper marginal portion thereof to the upper portion of the frame so that it is capable of swinging into and out of a closed position wherein it closes the frame interior, a horizontal lock bar part having one end thereof hinged to one of the side portions of the frame so that it is capable of swinging into and out of an operative position wherein it extends across the door part and serves to hold the latter in its closed position, and releasable bolt means extending normally between the other end of the lock bar part and the other side portion of the frame and operative when the lock bar part is in its operative position to urge it towards the door part with clamping pressure; a pair of complemental female and male members associated with the aforesaid parts respectively, formed independently of said releasable bolt means, and operative when the lock bar part is in its operative position so to coact and interfit with one another as to transmit the clamping pressure directly from the lock bar part to the door part, the female member being in the form of a pad formed integrally with the central portion of its associated part and having a substantially hemispherical socket facing the male member, said male member being in the form of a hemispherical head, having the flat surface of the head facing the central portion of its associated part, and embodying between it and said central portion of its associated part means whereby it is so loosely mounted that it is laterally movable in all directions to a limited extent and hence, in connection with swinging of the lock bar part into its operative position, automatically adjusts itself into proper seated relation with the socket in the pad of said female member.

2. In a door structure of the type that comprises a substantially vertical rectangular frame, a door hinged at the upper marginal portion thereof to the upper portion of the frame so that it is capable of swinging into and out of a closed position wherein it closes the frame interior, a horizontal lock bar having one end thereof hinged to one of the side portions of the frame so that it is capable of swinging into and out of an operative position wherein it extends across the door and serves to hold the latter in its closed position, and releasable bolt means extending normally between the other end of the lock bar and the other side portion of the frame and operative when the lock bar is in its operative position to urge it towards the door with clamping pressure; a pair of complemental female and male members associated with the door and lock bar respectively, formed independently of said releasable bolt means and operative when the lock bar is in its operative position so to coact with one another as to transmit the clamping pressure directly from the lock bar to the door, the female member being connected permanently to the central portion of the door, and the male member being positioned adjacent the central portion of the lock bar and embodying between it and said central portion of the lock bar means whereby it is so loosely mounted that it is laterally movable in all directions to a limited extent and hence, in connection with swinging of the lock bar into its operative position, automatically adjusts itself into proper interfitting relation with the female member, the last mentioned means comprising a horizontal bolt which extends loosely through an oversized hole arrangement in the central portion of the lock bar and has one end thereof fixedly connected to the male member and its other end provided with an abutment-forming element.

3. In a door structure of the type that comprises a substantially vertical rectangular frame, a door hinged at the upper marginal portion thereof to the upper portion of the frame so that it is capable of swinging into and out of a closed position wherein it closes the frame interior, a horizontal lock bar having one end thereof hinged to one of the side portions of the frame so that it is capable of swinging into and out of an operative position wherein it extends across the door and serves to hold the latter in its closed position, and releasable bolt means extending normally between the other end of the lock bar and the other side portion of the frame and operative when the lock bar is in its operative position to urge it towards the door with clamping pressure; a pair of complemental female and male members associated with the door and lock bar respectively, formed independently of said releasable bolt means, and operative when the bar is in its operative position so as to coact with one another as to transmit the clamping pressure directly from the lock bar to the door, the female member being in the form of a pad that is formed integrally with the central portion of the door and has a substantially hemispheric socket facing the male member, said male member being in the form of a hemispherical head, having the flat surface of the head fitting slidably against the central portion of the lock bar, and embodying between it and said central portion of the lock bar means whereby it is so loosely mounted that it is laterally movable in all directions to a limited extent and hence, in connection with swinging of the lock bar into its operative position, automatically adjusts itself into proper seated relation with the socket in the pad of said female member, the last mentioned means comprising a horizontal bolt which extends loosely through an oversized hole arrangement in the central portion of the lock bar and has one end thereof connected fixedly to the central portion of the head and the other end provided with a pair of abutting nuts.

4. In a door structure of the type that comprises a substantially vertical rectangular frame, a door hinged at the upper marginal portion thereof to the upper portion of the frame so that it is capable of swinging into and out of a closed position wherein it closes the frame interior, a hollow horizontal lock bar embodying spaced apart inner and outer side walls and having one end thereof hinged to one of the side portions of the frame so that it is capable of swinging into and out of an operative position wherein it extends across the door and serves to hold the latter in its closed position, and releasable bolt means extending normally between the other end of the lock bar and the other side portion of the frame and operative when the lock bar is in its operative position to urge it towards the door with clamping pressure; a pair of complemental female and male members associated with the door and lock bar respectively, formed independently of said releasable bolt means, and operative when the lock bar is in its operative position so as to coact with one another as to transmit the clamping pressure directly from the lock bar to the door, the female member being in the form of a pad that is formed integrally with the central portion of the door and has a substantially hemispherical socket facing the male member, said male member being in the form of a hemispherical head, having the flat surface of the head fitting slidably against the central portion of the lock bar, and embodying between it and said central portion of the lock bar means whereby it is so loosely mounted that it is laterally movable in all directions to a limited extent and hence, in connection with swinging of the lock bar into its operative position, automatically adjusts itself into proper seated relation with the socket in the pad, the last mentioned means comprising a horizontal bolt which extends loosely through oversized holes in the inner and outer side walls of the lock bar and has one end thereof connected fixedly to the central portion

of the head and its other end provided with a pair of abutting lock nuts and a horizontal sleeve extending loosely around the bolt and through the lock bar, having its ends fitting in the hole defining portions of the inner and outer side walls of the lock bar, and serving to prevent dust and other foreign matter from entering the interior of the lock bar via said holes.
